VERNON C. PORTER, OF NEW YORK, N. Y., ASSIGNOR TO CHARLES M. HIGGINS & CO., OF NEW YORK, N. Y., A COPARTNERSHIP COMPOSED OF CHARLES M. HIGGINS AND TRACY HIGGINS

ATTACHMENT FOR BOTTLES

Application filed December 10, 1927. Serial No. 239,025.

This invention relates to attachments for bottles, and aims to provide a simple, inexpensive and convenient attachment for an ink bottle.

5 An attachment embodying the invention engages the bottom and top of an ink bottle and embraces its neck. The attachment may be made of a single piece of sheet material. It may be used to hold a pen and brush on 10 the bottle, and, if desired, also to secure the bottle to a drawing board.

The invention may best be understood from a description of an illustrative embodiment thereof shown in the accompanying drawings, in which:

15 Fig. 1 is a side elevation of the attachment applied to an ink bottle;

Fig. 2 is a back elevation of the attachment applied to an ink bottle;

20 Fig. 3 is a front elevation of the attachment applied to an ink bottle;

Fig. 4 is a plan view of the attachment applied to an ink bottle; and

Fig. 5 is a view, on a smaller scale, of 25 the piece of sheet metal from which the attachment is made, indicating the lines on which the sheet metal is bent.

The attachment consists essentially of a strip of sheet metal bent on three parallel 30 lines 10, 11, and 12 to provide a bottom plate 13, a side bar 14 perpendicular to the bottom plate, a top bar 15 inclined inwardly from the side bar, and a neck piece 16 inclined outwardly from the top bar and perpendicular to the 35 bottom plate.

The neck piece 16 has lateral projections 17 which are bent around to provide a spring 40 clip to embrace the neck of the bottle so as to hold the attachment securely on the bottle.

The top bar 15 has lateral projections 18 45 terminating in notched tabs 19, which are bent at right angles to the projections 18 to provide spaced outer bearing elements of a pen holder whose inner bearing element is provided by the neck piece 16. Tabs 20 cut from the side portions of the side bar 14 and bent slightly outwardly from the plane of the side bar provide a brush holder.

The bottom plate 10 may be provided with 50 a hole 21 for the passage of the shank of a

thumb tack, so as to permit fastening the attachment and the ink bottle which it contains upon a drawing board.

What I claim is:

An attachment for ink bottles, comprising 55 a strip of sheet metal bent on three parallel lines to provide a bottom plate, a side bar perpendicular to the bottom plate, a top bar inclined inwardly from the side bar, and a neck piece inclined outwardly from the top bar 60 and perpendicular to the bottom plate, the neck piece having integral lateral projections which are bent around to provide a spring 65 clip to embrace a cylindrical bottle neck and the top bar being provided with integral lateral projections having at their ends 70 upturned tabs which cooperate with the neck piece to provide three points of support for a rod-like object placed horizontally across the attachment.

In testimony whereof I have hereunto set 75 my hand.

VERNON C. PORTER.
